UNITED STATES PATENT OFFICE.

JOHN L. BAUKUS, OF SAGINAW, MICHIGAN.

BAROMETER.

Application filed February 26, 1926. Serial No. 90,885.

The present invention relates to barometers, and the primary object of the invention is to provide a novel instrument of this character which will be effective in its operation for judging of the probable changes of weather. A further object of the invention is to provide a device of this character which is of simple and novel construction, and one wherein the member containing the 10 expansion medium, is supported in a novel manner for permitting of air to circulate freely about the member.

A further object of the invention resides in the novel manner in which the air bulb 15 of the barometer is supported upon the fluid containing bulb of the barometer.

Other objects and advantages of the invention will be apparent during the course 20 of the following detailed description, taken in connection with the accompanying drawing forming a part of this specification and in which drawing—

Figure 1 is a front plan view of a barometer constructed in accordance with my invention.

Figure 2 is a central vertical section through the same.

Figure 3 is a fragmentary detailed view 30 illustrating the manner of supporting one member of the barometer upon its companion member.

Figure 4 is a fragmentary perspective view of the upper end of the tube portion of the fluid containing bulb.

In the drawing, and wherein similar reference characters designate corresponding parts throughout the several views, the letter A may designate a supporting plate, for vertical supporting of the barometer which in 40 the example shown, comprises upper and lower separable companion sections B and C respectively.

The supporting plate A which may be formed of any suitable material, is provided 45 inwardly of its marginal edges with an opening formed with a vertically extending way 10 having an enlarged circular portion 11 formed at the upper end thereof and an enlarged circular portion 12 provided at the lower end thereof. This opening as clearly illustrated in Figure 2, extends through the plate A from the front face 13 of the plate to the rear face 14 thereof.

The upper section B of the barometer, and 55 which is preferably formed of glass, embodies a bulb like head 15 having flattened

front and rear faces 16 and 17 respectively, and from the lower portion of which bulb a tube 18 extends. The head 15 may be termed an air bulb, while the tube 18 may be 60 termed a gauge tube.

Referring now to the lower section C of the barometer, and which is also formed of glass, the same embodies a fluid bulb 20 having flattened front and rear surfaces 21 and 22 respectively, and from the upper portion of which bulb, a stand tube 23 of greater internal diameter than the external diameter of the gauge tube 18 extends. The upper end of the stand tube 23, is provided with 70 diametrically disposed projections 24 each having a crotch 25 formed in its upper edge and into which crotches the lower portion of the air bulb 15 rests.

When the sections B and C are in assembled relation, the gauge tube 18 extends coaxially within the stand tube 23 and when the air bulb 15 comes to rest upon the upper end of the stand tube, the lower end of the gauge tube extends into close proximity 75 with the bottom of the fluid bulb 20 as clearly illustrated in Figure 2. This positioning of the tube 18 within the tube 23, provides a pressure chamber 26 communicating at its lower end with the bulb 20, and at its upper end with the atmosphere through the diametrically disposed passageways 27 provided by the projections 24.

An expansion medium or indicating fluid of any preferred character is contained 80 within the bulb 20, and a column of which fluid is adapted to rise or fall within the gauge tube 18 upon varying atmospheric pressures acting upon the fluid in the bulb 20 through the chamber 26. A suitable scale 30 may be provided on the front face 13 of the supporting plate for determining the weight or pressure of the atmosphere, and hence judge the probable change of 85 weather.

The barometer may be supported in a vertical position within the opening formed in the supporting plate, by means of transversely extending straps 31 which span the vertically extending way 10, and have their 90 ends secured to the supporting plate by suitable fastening elements 32. These straps 31 are preferably disposed one at the front of the supporting plate, at a point substantially 95 midway of the way 10, and two at the rear 100 face of the supporting plate at points relatively near each end of the way 10. These 105

straps 31, and as clearly illustrated in Figure 2, engage the stand tube 23 in a manner for rigidly supporting the tube in a vertical position within the way 10 and out of contact with the side walls of the way, and the fluid bulb 20 in spaced relation to the circular wall of the cut-out portion 12. When the lower section C is supported in this manner, the upper section B which rests loosely upon the upper end of the stand tube 23, is disposed out of contacting relation with the circular wall of the upper cut-out portion 11. Thus it will be seen that air is permitted to circulate freely around the glass sections of the barometer.

It is preferred that the thickness of the bulbs 15 and 20 be of a dimension to lie at least inwardly of the front and rear faces of the supporting plates for preventing possible damage to the bulbs, and that the crotches 25 provided at the upper end of the stand tube be so disposed that when the faces of the fluid bulb 20 are in parallel relation with the front and rear faces of the supporting plate, and the bulb 15 comes to rest within the crotches, the section B will be held against relative rotation with respect to the section C, and with the flattened surfaces 16 and 17 in parallel relation with the front and rear faces of the supporting plate.

From the foregoing description it will be apparent that a novel type of barometer has been provided embodying a pair of separable companion sections of relatively like configuration, with one of said sections adapted to telescopically receive a portion of the companion section in a manner to serve as a support for the section.

Changes in detail may be made to the form of invention herein shown and described, without departing from the spirit of the invention or the scope of the following claims.

I claim:

1. A device of the class described comprising a lower section embodying a bulb for containing fluid and a vertical stand tube having diametrically disposed crotches provided in its upper end, and an upper section embodying a bulb for containing air resting in said crotches of the stand tube and having a depending gauge tube extending downwardly through the stand tube into a liquid contained in the bulb for containing fluid.

2. A device of the class described comprising a lower section embodying a bulb for containing fluid and provided with a vertically extending stand tube, and an upper section embodying a bulb for containing air resting upon the upper end of the stand tube and having a depending gauge tube of less external diameter than the internal diameter of the stand tube, extending downwardly

through the stand tube into a liquid contained in the bulb for containing fluid of the lower section.

3. A device of the class described comprising a lower section embodying a bulb for containing fluid having diametrically disposed flattened surfaces and a vertically extending stand tube having diametrically disposed crotches provided in its upper end, and an upper section embodying a bulb for containing air and having diametrically disposed flattened surfaces, resting in the crotches of the stand tube for retaining the flattened surfaces of the respective bulbs in parallel planes, said bulb of the upper section being provided with a depending gauge tube extending downwardly through the stand tube and out of contacting relation with the inner surface thereof.

4. A device of the class described comprising a lower section embodying a bulb for containing fluid and a stand tube having projections provided at its upper end, and an upper section embodying a bulb for containing air and a gauge tube of less external diameter than the internal diameter of the stand tube, said bulb for containing air to rest upon the projections of the stand tube with the gauge tube extending downwardly through the stand pipe, in a manner whereby passageways will be provided at the upper end of the stand tube through which air may pass into the stand tube for acting upon a liquid contained in the bulb of the lower section for causing a rise and fall of a column of the liquid within the gauge tube.

5. A device of the class described comprising a supporting plate having a vertically extending opening provided therein, a lower barometer section embodying a bulb for containing fluid and a vertical stand tube, rigidly secured within the opening of the supporting plate and out of contacting relation with the plate, and an upper barometer section embodying a bulb for containing air resting loosely upon the upper end of the stand tube out of contacting relation with the supporting plate and a depending gauge tube extending downwardly through the stand tube into a liquid contained in the bulb for containing fluid.

6. A device of the class described comprising a supporting plate, a lower barometer section embodying a bulb for containing fluid and a vertical stand tube, rigidly supported upon the plate out of contact therewith, and an upper barometer section embodying a bulb for containing air resting loosely upon the upper end of the stand tube and a gauge tube extending downwardly through the stand tube in coaxial relation thereto.

JOHN L. BAUKUS.
